US0D1106007S

(12) United States Design Patent (10) Patent No.: US D1,106,007 S
(45) Date of Patent: * Dec. 16, 2025

(54) CAR CENTER CONSOLE

(71) Applicant: AUTOMOBILI LAMBORGHINI S.P.A., Sant'Agata Bolognese (IT)

(72) Inventor: Mitja Borkert, Castelnuovo Rangone (IT)

(73) Assignee: Automobili Lamborghini S.p.A., Sant'Agata Bolognese (IT)

() Term: 15 Years

(21) Appl. No.: 29/945,105

(22) Filed: May 31, 2024

Related U.S. Application Data

(62) Division of application No. 29/860,642, filed on Nov. 21, 2022, now Pat. No. Des. 1,040,712.
